CLAIM

The ornamental design for the temples for eyeglasses, as shown and described.

DESCRIPTION

FIG. 1 is a right front perspective of the temples as attached to the eyeglass frame, which is not claimed;

FIG. 2 is a left front perspective view of the temples attached to the eyeglass frame, which is not claimed;

FIG. 3 is an inside elevational view of the right temple;

FIG. 4 is an inside elevational view of the left temple;

FIG. 5 is a top plan view of the right temple;

FIG. 6 is bottom view of the right temple; and,

FIG. 7 is front perspective view of the left temple.

The temples have gemstones or other material which contrasts with the temples mounted towards the connection point to the eyeglass frames and on the inside distal ends of the temples.

The temple for eyeglasses is shown separately in FIGS. 3-7 for ease of illustration only.
